The ornamental design for container having recessable neck, as shown and described.

DESCRIPTION

The present invention relates generally to containers, and, more specifically, to a container having a recessable neck. FIG. 1 is a perspective view of the container of the present invention.

FIG. 2 is a front view of the container of the present invention, shown on a reduced scale.

FIG. 3 is a rear view of the container of the present invention, shown on a reduced scale.

FIG. 4 is a left side view of the container of the present invention, shown on a reduced scale.

FIG. 5 is a right side view of the container of the present invention, shown on a reduced scale.

FIG. 6 is a top view of the container of the present invention; and,

FIG. 7 is a bottom view of the container of the present invention.
